Primary Examiner — Mitchell I. Siegel

(74) Attorney, Agent, or Firm — Greenberg Traurig, LLP

(57) **CLAIM**

The ornamental design for a golf iron set, as shown and described.

DESCRIPTION

FIG. 1 is a perspective view of a golf iron set, each having our design;

FIG. 2 is a front view of the golf iron set of FIG. 1;

FIG. 3 is a rear view of the golf iron set of FIG. 1;

FIG. 4 is a left side view of the golf iron set of FIG. 1;

FIG. 5 is a right side view of the golf iron set of FIG. 1;

FIG. 6 is a top view of the golf iron set of FIG. 1; and,

FIG. 7 is a bottom view of the golf iron set of FIG. 1; and, FIG. 8 is an enlarged front view taken of circles 8-8 of FIG. 2.

Portions of the golf iron set shown in broken lines form no part of the design claimed.

Portions of the design shown with stippling indicate a contrasting shade or color from non-stippled portions.

1 Claim, 8 Drawing Sheets---
